UNITED STATES PATENT OFFICE.

RUSSELL O. COVELL, OF PHILADELPHIA, PENNSYLVANIA, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 23, 1924. Serial No. 695,667.

To all whom it may concern:

Be it known that I, RUSSELL O. COVELL, a citizen of the United States of America, residing at Philadelphia, in the county of 5 Philadelphia and State of Pennsylvania, have invented certain new and useful Improvements in Telephone-Exchange Systems, of which the following is a full, clear, concise, and exact description.

10 This invention relates to a telephone exchange system and more particularly to a system in which connections are established by means of machine switching apparatus.

In exchange systems of the above mentioned 15 character it is desirable to enable connections to be established from distant toll points to any subscriber's line in a machine switching exchange area over the automatic switching mechanism of the exchange. In 20 the establishment of such connections it is further desirable under certain conditions to signal the local operator in the machine switching exchange in order that such operator may aid the distant toll operator in 25 the obtaining of connections which otherwise might not be established due to lack of proper information or failure of the equipment to respond to the dialing operations of the toll operator.

30 For this purpose a special operator's position known as the outward delay operator is associated with the incoming end of the toll line at the machine switching exchange and provision is made for signaling this operator whenever a machine switching sender fails to respond to dial pulses from the distant toll office or when the distant toll operator dials the particular code assigned for calling this outward delay operator. To

35 enable this special operator to be thus called provision is made in the senders of the machine switching exchange, of means operative if no impulses are recorded upon the registers of the senders, or if a particular two-digit number is dialed by the toll operator.

40 It is further desirable in the establishment of toll connections to enable the establishment of calls to other operators' positions in the mechanical exchange in addition to the usual calls to the zero operator, to the information, repair, long distance or commercial operators. These additional operator calls are made in accordance with this invention by dialing codes of two digits only,

the first of the digits always being the digit 1. These digits through a special organization of the sender are both recorded upon a single register preferably the "A" code register, the translator of the sender being then set in the usual manner from the banks of the single register in accordance with the summation of the two digits recorded. As above intimated one of these special codes, 13, is employed in signaling the outward delay operator, in which instance the translator of the sender takes no setting.

45 It is therefore an object of this invention to provide an improved sender for enabling distant toll operators to control the establishment of connections through machine switching exchanges.

50 A feature of the invention resides in the provision of means in a central office sender for successively registering two digits of a number upon a single register, only when the first of said digits has a particular numerical value.

55 A further feature of the invention resides in the provision of means for initiating a particular signaling operation in case a special two digit number is registered upon a single register of the sender.

60 A still further feature of the invention resides in the provision of a circuit local to the sender, for holding the dialing impulse relay of the sender operated for a predetermined interval following the seizure of the sender, for preventing the false release of the relay prior to the commencement of dialing. A false release of the relay might otherwise arise from disturbances in the toll line following its connection with the sender.

65 These and other features of the invention will appear from a consideration of the drawings and appended claims.

70 Referring to the drawings, Fig. 1 shows a district selector which may be taken for use by line switches in which incoming toll lines terminate and which may extend connections to a desired district or office of the exchange, the control circuits therefor and, in the lower portion of the figure, the sender selector for associating an idle operator's sender with the district selector. Fig. 2 shows as much of a central office sender as is necessary to an understanding of the invention. In this figure the sender monitor switch is shown in detail in the lower left portion of the figure and in the right portion 75

of the figure a register steering switch and the "A" and "B" code registers are illustrated. The numerical registers have been omitted in order to simplify the drawing.

5 The toll line and associated equipment and the line switch in which the toll line terminates and which has access directly to the district selector of Fig. 1 have been omitted from this disclosure, being considered unnecessary to a full understanding of 10 this invention. For a full disclosure of these circuits reference may be had to the application of William C. Jordan, Serial No. 680,807, filed December 15, 1923.

15 The district selector of Fig. 1 is of the well known power driven panel bank type such as disclosed in the patent to E. B. Craft and J. N. Reynolds No. 1,123,696, issued January 5, 1915, the circuits of this 20 selector being identical with the circuits of the corresponding selector disclosed in the aforementioned application of William C. Jordan.

25 The sender diagrammatically illustrated in Fig. 2 is of the general type disclosed in the patent to O. H. Kopp, No. 1,509,434, granted Sept. 23, 1924. Only such portions of the sender have been disclosed as are considered essential to an understanding of the 30 present invention.

35 The district selector of Fig. 1 may have access to subscribers' lines in the machine switching exchange through incoming and final selector switches in the manner fully disclosed in the above mentioned application of William C. Jordan. These switches have been omitted from this disclosure in order that the disclosure may be simplified.

40 The invention will be best understood from a detailed description of the manner in which a toll connection may be established. It being assumed that the distant toll operator has initiated a toll connection to the exchange area in which the district selector 350 is located, she obtains a connection 45 with the idle selector 350 in the manner fully set forth in the above mentioned application of W. C. Jordan. As soon as the district selector is seized by the toll line switch a circuit is established which may be traced in part from battery, through the winding of sleeve relay 303, terminal 275, and thence to ground at the line switch. Relay 303 upon operating disconnects battery potential from the multiples of terminal 220 by opening the circuit extending from the terminal 220, over the lower contacts of cam 301, the left back contact of relay 302, the outer right back contact of relay 303, the upper contacts of cam 304 to battery through resistance 305, thus marking the district selector busy to all line switches having access thereto.

45 At its inner right front contact relay 303 establishes a circuit for relay 307 which may

be traced from battery, through the left winding of relay 307, the left contacts of cam 306, to ground at the inner right front contact of relay 303. Relay 307 upon energizing closes a circuit for advancing sequence switch 310 out of its normal position 1 into position 2, this circuit extending from battery through the magnet winding of sequence switch 310, the upper left contact of cam 324, the outer left front contact of relay 307 to ground at the right contact of cam 308. As soon as the sequence switch leaves position 1, the original energizing circuit of relay 307 is opened at the upper left contact of cam 306 but relay 307 is maintained energized at this time over a locking circuit extending through its right winding, right front contact, the lower right and upper left contacts of cam 309 to ground. With sequence switch 310 in position 2 and relay 307 energized, a circuit is established for starting the hunting movement of the sender selector switch 325 in search of an idle central office sender. The switch starts through the operation of start magnet 311 over a circuit extending from battery through its winding, the back contact of relay 315, the left contacts of cam 308, thence to ground through the inner right front contact of relay 303. Magnet 311, upon energizing, closes an obvious circuit for the rotary magnet 312 of the switch 325, the switch 325 being advanced only until its test brush 313 encounters a test terminal upon which full battery potential is encountered. All idle senders are marked by full battery potential on the multiple test terminals thereof appearing in the banks of all sender selector switches. It will be assumed that the sender shown in Fig. 2 is the first idle sender encountered. When, therefore, brush 313 engages terminal 317 a circuit is established from battery through the back contact of relay 314, terminal 317, brush 313, both windings of relay 314, winding of relay 315 to ground through the lower contact of cam 316. Relay 314 energizes in this circuit but relay 315 does not energize due to the inclusion of the high resistance right winding of relay 314 in series therewith. As soon, however, as relay 314 energizes, it short circuits its own right winding, thereby changing the potential on the multiples of test terminal 317 for marking the selected sender as busy to all sender selectors having access thereto and permitting sufficient current to flow through the winding of relay 315 to cause its energization. With relay 315 energized, the circuit of start magnet 311 is opened, whereupon the circuit of rotary magnet 312 is opened and the brushes of the sender selector brought to rest. At its front contact, relay 315 also establishes a circuit for relay 318 which may be traced from battery through resistance 130

305, winding of relay 318, front contact of relay 315, left contacts of cam 308 to ground at the inner right contact of relay 303. Relay 318 upon energizing locks over 5 its innermost right contact and the inner left contact of relay 319 to ground at the inner right front contact of relay 303. At its intermediate right armature contacts, relay 318 prepares the fundamental circuit 10 over brushes 326 and 327. At its left front contact, relay 318 establishes a circuit for advancing sequence switch 310 out of position 2 and into position 3. This circuit may be traced from battery, through the 15 winding of sequence switch 310, the lower right and upper left contacts of cam 320 to ground at the left front contact of relay 318. As soon as sequence switch 310 leaves position 2, the holding circuit of relay 307 20 is opened at the lower right contact of cam 309, and relay 307 thereupon deenergizes.

With sequence switch 310 in position 3 and relay 318 energized, a circuit is established for relay 402 of the selected sender 25 and relays 302 and 323 of the district selector. This circuit may be traced from battery, through the winding of relay 323, the upper right and lower left contacts of cam 321, and in parallel therewith from battery 30 through the winding of relay 302 and the lower contacts of cam 321, thence over the outer right contact of relay 318, brush 322, left back contact of relay 401, intermediate and left windings of relay 402 to ground. 35 Relay 323 being marginal does not operate in this circuit but relays 302 and 402 operate, relay 302 being functionless at this time. Upon the operation of relay 402, an obvious circuit is established for relay 400 which at 40 its contact removes battery potential from the multiples of test terminal 317, thereby marking the selected sender as busy to all the sender selectors having access thereto. Relay 402 also closes a circuit in parallel with 45 the circuit for relay 400, extending over brush 405 and the normal contact of the bank of monitor switch 450 with which it is associated, to battery through the winding of relay 403, and to battery through the inner 50 right normal contact and winding of relay 404. With relays 403 and 404 both energized, a circuit is established for relay 406 which may be traced from battery, through the winding of this relay, the brush 407 and 55 normal contact of the bank with which it is associated, the right contact of relay 403 to ground at the outer left front contact of relay 404. Relay 406 energizes, closing a circuit from ground, through the outer 60 left front contact of relay 404, the right contact of relay 403, the brush 407, inner left contact of relay 406, to battery through the back contact and winding of stepping magnet 408. The stepping magnet 408 thereupon energizes advancing the brushes of the

switch 450 to their first position terminals, whereupon the circuit of relay 406 is opened at brush 407 and relay 403 deenergizes opening the circuit of magnet 408 arresting the movement of the switch. 70

Upon the energization of relays 404 and 403, a circuit was also established from ground over the outer left front contact of relay 404, the right contact of relay 403, the inner left contact of relay 404, conductor 409, brush 328, the lower right and upper left contacts of cam 329, the inner upper contact of relay 330, to terminal 231, for causing the operation of a signal at the toll operator's position to apprise her that a 75 sender has been seized and that she may proceed to dial. 80

At the time relay 404 of the sender energized, it locked itself up, the circuit extending through its winding and its inner right front contact to ground at the left contact of relay 402, which circuit maintains relay 404 energized after switch 405 leaves position 1 and opens the initial energizing circuit of relays 404 and 403. Relay 403, 85 however, deenergizes as soon, following the advance of switch 450 to position 1, as its slow releasing characteristic permits. 90

At the time the sender was seized and the district sequence switch advanced into position 3, a dialing circuit was established extending from battery, through the winding of the impulse relay 410 of the sender, over conductor 411, brush 331, the left contacts of cam 332, the lower back contact of relay 330 to terminal 232, this circuit being completed in the manner set forth in the aforementioned application of W. C. Jordan. Relay 410 energizes in this circuit. To insure that relay 410, after being energized, 95 is not disturbed during the period elapsing from the seizure of the sender through the period during which the dialing signal is being transmitted, relay 410 is held energized in a local circuit extending through its winding, the right winding of relay 412 and to ground at the left contact of relay 403. This local circuit is, however, opened as soon as relay 403 becomes deenergized. 100 Upon the energization of relay 410, an obvious circuit is prepared for the slow releasing relay 413. Relay 413 in turn prepares an obvious circuit for relay 414. With relays 413 and 414 both energized, the stepping magnet 417 of the first, "A", code register is placed under the control of the impulse relay 410. 110

The operator now actuates her dial in accordance with the first digit of the number of the desired line, this digit being the first 125 code letter of the office designation, whereupon the circuit over terminal 232, the lower back contact of relay 330, the left contacts of cam 332, brush 331, conductor 411 to battery through the winding of impulse relay 410 130

is periodically opened. This impulse relay thereupon follows the interruptions of the dial contacts and effects the setting of the "A" code register.

5 Upon the first deenergization of relay 410, a circuit is established from ground at its back contact over the left front contact of relay 413, winding of relay 415, brush 416 of the steering switch 425 and the normal contact upon which it is standing, the winding of stepping magnet 417 to battery through the left winding of off-normal relay 418. Magnet 417 and off-normal relay 418 energize in this circuit, relay 418 connecting ground over its contact to the off-normal conductor 432 for holding the relays 400 and 404 energized independently of relay 402. Relay 415 also energizes in the circuit of magnet 417 and at its armature 10 and front contact closes a circuit through the magnet winding 421 of the steering switch 425 preparatory to advancing the steering switch upon the termination of the first series of impulses. A second circuit is 15 also established at this time for relay 420 which may be traced from battery, through the winding of relay 420, the inner right contact of relay 414, brush 419 and the normal terminal upon which it is standing, the 20 armature and back contact of magnet 417, the normal contact and brush 416 of switch 425, thence as traced, through the winding of relay 415 to ground at the back contact of relay 410. Relay 420 energizes in this 25 circuit and at its right contact connects ground directly to the winding of relay 413 to insure that this relay will remain energized until the stepping magnet 417 has completed its stroke. At its left contact, 30 relay 420 connects ground to one terminal of relay 415 for maintaining the relay 415 energized irrespective of the continued deenergization of relay 410. As soon as magnet 417 completes its forward stroke, the 35 circuit of relay 420 is opened and the holding circuits of relay 413 and relay 415 are opened. Thus, the complete energization of magnet 417 is insured regardless of the period that relay 410 remains deenergized. 40 When relay 410 again energizes, the circuit previously traced for relay 415 and magnet 417 is opened and magnet 417 deenergizes, advancing the first code register one step. Relay 415, however, being slow to release 45 does not have time to retract its armature in the brief periods during which relay 410 is deenergized. Thus, in response to each deenergization and energization of relay 410, magnet 417 advances the "A" code 50 register one step.

Upon the termination of the first series of impulses, relay 410 remains energized for a sufficient time to permit relay 415 to retract its armature, whereupon the circuit of magnet 421 of the steering switch is

opened and the steering switch advances its brushes one step. With the steering switch in position 1, magnet 422 is operated, in response to the operation of impulse relay 410, for advancing the brushes of the "B" code register to positions corresponding to the digit value of the second code digit dialed. Following the dialing of the code digits of the desired line, the toll operator dials the numerical digits, whereupon the 55 numerical registers, not shown, of the sender are operated to register the numerical designation of the desired line. Following the registration of the complete line designation, the translator switch, not shown, is set in accordance with the combined settings of the "A" and "B" registers in the manner fully set forth in the application of O. H. Kopp hereinbefore referred to, and the circuits of the sender are prepared for 60 controlling the setting of automatic switches to extend the connection to the terminals of the desired line. In the preparation of the sender circuits, the sequence switch thereof, the cams of which are illustrated 65 in the upper portion of Fig. 4, is advanced out of its normal position 1 into position 2 preparatory to controlling the district selector 350 in its brush selection movement. 70

It will be recalled that the sequence switch 310 of the district selector 350 was advanced to position 3 following the selection of the sender and, therefore, with the sequence switch of the sender in position 2, a fundamental switch controlling circuit is 75 established between the circuits of the district selector 350 and the sender which may be traced from battery through the right winding of relay 307, the lower contacts of cam 333, contact 356 of relay 318, brush 327, the right back contact of advance relay 401, the windings of the sender stepping relay 430, the back contact of relay 428, contact of cam 427, winding of polarized overflow relay 424 to ground through the left contacts of cam 426. Relays 307 and 430 energize in this circuit but relay 424 being polarized does not receive current of the right polarity to cause its operation. Relay 430 upon energizing closes a circuit, not shown, 100 in the well known manner for associating a proper pair of counting relays with contacts of the translator switch for controlling district brush selection. 105

At the district selector, relay 307 upon 110 energizing closes a circuit for advancing sequence switch 310 out of position 3 into position 4, which circuit may be traced from battery, through the magnet winding of the sequence switch, the upper left contact of cam 324, the outer left front contact of relay 307 to ground at the right contact of cam 308. As soon as the sequence switch advances out of position 3, the initial energizing circuit of relay 307 previously 115

- traced is opened at the lower left contact of cam 333, but relay 307 is maintained energized in series with the stepping relay 430 over a circuit which may now be traced 5 from battery, through the right winding and right front contact of relay 307, the upper left and lower right contacts of cam 333, and thence over the circuit traced to ground, at the lower left contact of cam 10 426. With relay 307 energized and sequence switch 310 in position 4, a circuit is established for the up-drive magnet 334 of the switch 350 for advancing the switch shaft in its brush selecting movement. This circuit 15 may be traced from battery, through the winding of magnet 334, the lower right contact of cam 335, the outer left front contact of relay 307 to ground at the right contact of cam 308. As the switch shaft 20 advances in its brush selection movement, the commutator brush 338 engages segments of commutator strip 337, whereupon a circuit is intermittently established in shunt of the winding of stepping relay 430 which 25 may be traced from battery, through the right winding of relay 307, right front contact of this relay, the upper left contact of cam 333, the upper right contact of cam 336, commutator strip 337, brush 338 to 30 ground at the upper left contact of cam 339. Relay 307 is maintained energized over this shunt circuit but relay 430 deenergizes each time that the brush 338 engages a conducting portion of the strip 337 corresponding 35 to a brush tripping position.
- In response to the intermittent operation of relay 430, counting relays of the sender operate successively in pairs in the well known manner until the 0' counting relay 431 energizes in parallel with relay 428, the operated counting relays locking to ground over the contacts of cam 429. With relays 431 and 428 energized, relay 428 opens the fundamental switch controlling circuit previously traced and relay 431 establishes a circuit in a well known manner for advancing the sender sequence switch out of position 2 into position 4. As soon as the sequence switch leaves position 2, the operated counting relays are released through the opening of the contacts of cam 429. The circuits of the sender are now in condition for controlling the group selection movement of the district selector 350.
- At the district selector, upon the opening of the fundamental circuit, relay 307 deenergizes as soon as the brush 338 engages the next insulating segment of the commutator strip 337 and at its outer left back contact establishes a circuit for advancing sequence switch 310 out of position 4 into position 5. This circuit may be traced from battery, through the magnet winding of sequence switch 310, the lower left contact of cam 324, the outer left back contact of relay 307 to ground at the right contact of cam 308. With the sender sequence switch in position 4 and sequence switch 310 of the district selector in position 5, the previously traced fundamental switch controlling circuit is again established through the windings of sender stepping relay 430 and the right winding of relay 307. Relay 307 again energizes closing the previously traced locking circuit for itself over the upper left and lower right contacts of cam 333, and advances sequence switch 310 into position 6. As sequence switch 310 advances from position 5 into position 6, an obvious circuit is closed for the trip magnet 343, extending over the lower right contact of cam 339 for energizing this magnet to trip the selected set of brushes upon the next subsequent upward movement of the switch shaft.
- With sequence switch 310 in position 6 and relay 307 energized, the previously traced circuit for the up-drive magnet 334 is again established and the switch shaft is driven upwardly. During the first portion of this upward movement, the selected set of brushes is tripped through the operation of magnet 343 in the well known manner, and thereafter the tripped set of brushes advances in contact with the terminals of its associated bank. During the continued upward movement of the switch shaft, the brush 341 engages the commutator strip 340 for intermittently shunting the stepping relay 430 of the sender each time that the selected set of brushes approaches the bottom of a group of bank terminals. This shunt circuit may be traced from battery, through the right winding and right front contact of relay 307, the upper contacts of cam 333, commutator strip 340, brush 341 to ground at the upper left contact of cam 339. Relay 307 is maintained energized over this shunt path but relay 430 deenergizes each time that the brush 341 encounters a conducting portion of the strip 340 and in the well known manner causes the successive energization of pairs of counting relays. The operated counting relays are again locked over the contact of cam 429. As soon as the district brush shaft has advanced to such a position as will satisfy the district group registration of the sender, the 0' counting relay 431 energizes in parallel with relay 428, the relay 431 advancing the sender sequence switch into position 6, releasing the operated counting relays and preparing the circuits of the sender for the next selection control, and relay 428 opens the fundamental switch controlling circuit previously traced.
- As soon, following the opening of the fundamental circuit, as the brush 341 engages the next insulating segment of commutator strip 340, relay 307 deenergizes opening the

circuit of the up-drive magnet 334 and closing the previously traced circuit for advancing the sequence switch 310 out of position 6 into position 7. The selected set of brushes 5 has now been positioned in engagement with the lowermost set of terminals in a desired group of its bank.

With sequence switch 310 in position 7, relay 307 is energized in a local circuit which 10 may be traced from battery through its left winding, the left contacts of cam 306 to ground at the inner right contact of relay 303 and at its outer left front contact closes a circuit for advancing sequence switch 310 15 out of position 7 into position 8 which may be traced from battery through the magnet winding of the sequence switch, the upper left contact of cam 324, the outer left front contact of relay 307, the upper left contact 20 of cam 308, to ground at the inner right contact of relay 303. As the sequence switch leaves position 7½, the previously traced operating circuit of relay 307 is opened at the upper left contact of cam 306 but if, however, 25 the trunk terminating in the first set of terminals, upon which the brushes are resting, is at the time busy, as will be assumed, relay 307 remains energized over a locking circuit which may be traced from battery 30 through its right winding and inner left contact, the lower contacts of cam 344, test brush 342 to ground on the test terminal of such first busy trunk. When, therefore, sequence switch 310 reaches position 8, since 35 relay 307 is energized, the previously traced circuit of the up-drive magnet 334 is established and the switch shaft is driven upwardly in a trunk hunting movement. So long as the brush 342 encounters busy 40 ground potential on the test terminals of the trunks over which it passes, relay 307 will be maintained energized and the circuit of the up-drive magnet will remain closed. When, however, the first idle trunk is encountered, having no ground potential upon 45 the test terminal thereof, the locking circuit of relay 307 is destroyed and as soon thereafter as the brushes are properly centered relay 307 deenergizes opening the circuit of 50 up-drive magnet 334 and closing the previously traced circuit for advancing sequence switch 310 out of position 8 into position 9. Until the brushes are centered relay 307 is held over its left winding, lower left and 55 upper right contacts of cam 306, commutator strip 348, brush 347, upper contact of cam 335, outer left front contact of relay 307 to ground at the lower right contact of cam 308. 60 As soon as relay 307 deenergizes, busy ground potential is connected over the test brush 342 to the test terminal of the selected trunk over the brush 351, the overflow strip 349 of the commutator, the lower contacts of cam 65 309, the right back contact of

relay 307 to ground at the upper left contact of cam 357. After sequence switch 310 reaches position 8½, ground potential is connected to the brush 342 over brush 351 and strip 349 and the left contacts of cam 70 309 independently of relay 307.

As soon as sequence switch 310 reaches position 9, a circuit is established for reenergizing relay 307, which circuit extends from battery, through the left winding of relay 75 307, the lower contacts of cam 306, the right contact of relay 302, this relay having energized, as will be recalled, immediately upon the seizure of the sender, thence over the inner lower back contact of relay 353 to ground at the upper right contact of cam 339. As soon as relay 307 energizes, the previously traced circuit is established for advancing sequence switch 310 into position 10, or the selection beyond position. From 80 this point the sender functions in the well known manner to control the further extension of the desired connection. For a description of these functions reference may be had to the above mentioned application 85 of William C. Jordan.

As soon as the last selective control has been exercised by the sender a circuit is established back to the sender traceable in part from brush 345, upper back contact of relay 353, upper right and lower left contacts of cam 354, contact 356 of relay 318, brush 327, right contact of relay 401, windings of relay 430, back contact of relay 428, cam contact 427, winding of polarized relay 424, upper left and lower right contacts of cam 426, brush 326, contact of relay 318, lower left and upper right contacts of cam 355, lower back contact of relay 353 to brush 346. The current flows in this circuit in 100 such a direction as to cause the energization of both relays 430 and 424.

Upon the operation of the polarized relay 424, an obvious circuit is closed for relay 401 which opens the fundamental circuit and at its left contact opens the shunt around the right winding of relay 402. The current now flowing through the windings of relay 402 over the circuit previously 105 traced to battery through the winding of relay 302 is now decreased to such an extent that relay 302 deenergizes opening the holding circuit of relay 307 extending through the right front contact of relay 302, whereupon relay 307 deenergizes. With relay 307 110 deenergized, a circuit is now closed for advancing sequence switch 310 out of position 10 into position 11, which circuit may be traced from battery through the winding of sequence switch magnet 310, the lower left contact of cam 324, the outer left back contact of relay 307 to ground at the right contact of cam 308. In advancing from position 10 to position 11, the previously 115 traced circuit for relays 430 and 424 is 120

opened in turn releasing relay 401. With sequence switch 310 in position 11, a circuit is established for the relay 330 extending from battery, through the lower winding of this relay, the upper right and lower left contacts of cam 358 to ground through the left front contact of relay 318, thus opening the tip and ring leads and disconnecting the winding of supervisory relay 359 during the talking selection operation of the district selector 350.

A circuit is also established at this time for relay 307 which may be traced from battery, through its right winding, the lower contacts of cam 333, contact 356 of relay 318, brush 327, the back contact of relay 401, winding of stepping relay 430, the back contact of relay 428, the contact of cam 427, now closed in position 16, the winding of relay 424 to ground over the left contacts of cam 426. Relays 307 and 430 energize in this circuit, relay 307 closing a circuit from battery through the winding of magnet 310, over the upper left contact of cam 324, the outer left front contact of relay 307 to ground at the right contact of cam 308 for advancing sequence switch 310 out of position 11. After sequence switch 310 leaves position 11, its driving circuit is maintained closed over the upper left contact of cam 308 to the inner right front contact of relay 303 to insure its continued movement through successive talking selection positions. As the sequence switch continues to rotate, an intermittent shunt is placed around the windings of sender stepping relay 430, extending from battery, through the right winding and right front contact of relay 307 to ground through the lower right and upper left contacts of cam 309. Relay 307 is maintained energized over the shunt path but stepping relay 430 of the sender intermittently deenergizes for controlling the talking selection by successively operating pairs of counting relays at the sender in accordance with the talking selection registration of the translator switch of the sender. When the sender is satisfied with respect to its talking selection registration, the fundamental circuit is opened through the operation of relay 428 in the well-known manner and the circuit of relay 307 is opened. Upon the deenergization of relay 307, the circuit of sequence switch magnet 310 is opened and the sequence switch comes to rest in one of the talking selection positions 12, 14 or 16, for example 14. Relay 307 upon deenergizing also closes a circuit extending from the left terminal of relay 318 over the uppermost front contact of relay 330, the left contacts of cam 360, the outer left back contact of relay 307, the upper left contact of cam 308 to ground at the inner right contact of relay 303, thereby shunting relay 318 and causing its de-

energization. With relay 318 deenergized, the circuit previously traced through the windings of relay 402 and the windings of relays 302 and 323 is opened causing the release of relay 402.

When sequence switch 320 advances out of position 10½ the circuit previously traced for relay 410 is opened at the left contact of cam 332, and relay 410 thereupon releases, in turn releasing relays 413 and 414. Relay 413 upon deenergizing, establishes a circuit from ground at its right normal contact through brush 435, and the contacts of the restoring bank of the steering switch 425, back contact and winding of stepping magnet 421, to battery through the right winding of relay 418. Magnet 421 operates in this circuit advancing the brushes of the steering switch to their normal positions, the circuit of magnet 421 being interrupted at brush 435 when that brush reaches normal. Relay 414 upon deenergizing establishes a circuit for the stepping magnet 417 of the A register which may be traced from battery, through the left winding of relay 418, the winding and contact of magnet 417, contacts of the restoring bank and brush 433 of the register to ground at the outer right back contact of relay 414. Magnet 417 advances the brushes of the register to normal position, in which position the brush 433 extends the restoring circuit through brush 434 of the "B" register and the winding of magnet 422 to battery. Magnet 422 energizes in this extended restoring circuit, restoring the brushes of the "B" register to normal. In a similar manner, the remaining registers of the sender are restored to normal.

Upon the deenergization of relay 402, and the removal of ground from the off normal conductor 432 of the sender, the holding circuit of relay 404 is opened. This relay deenergizes, closing a circuit for relay 406 which may be traced from battery, through the winding of this relay, brush 407 and the off normal contacts of the bank with which it is associated to ground at the outer left back contact of relay 404. In response to the energization of relay 406, a circuit is established from battery, through the winding and back contact of stepping magnet 408 of the monitor switch 450, the inner left contact of relay 406 and thence to ground over brush 407 and the outer left back contact of relay 404. Magnet 408 energizing in this circuit, advances the brushes of the monitor switch from whatever position they are standing in at the time into their normal position, in which position the circuits of relay 406 and magnet 408 are opened. The deenergization of relay 402 also closes circuits, not shown, for restoring the remaining apparatus of the sender to normal,

Since, however, the manner in which this is accomplished does not intimately concern this invention, these restoring operations will not be further discussed or described 5 herein.

Upon the advance of sequence switch 310 of the district selector into position 14, relay 330 is held energized in a circuit which may be traced in part from battery, through 10 its lower winding, the upper contacts of cam 358, the lower front contact of relay 330, terminal 232 and thence to ground at the toll operator's position. Thus relay 330 is maintained energized until the toll operator 15 receives a trunk closure signal as will hereinafter be described. A circuit is now established for supervisory relay 359 which may be traced in part from battery at the incoming selector, not shown, brush 346, 20 lowermost contact of relay 353, upper contacts of cam 355, winding of relay 359, the upper contacts of cam 354, uppermost back contact of relay 353, brush 345 and thence to ground at the incoming selector. Relay 359 25 energizes in this circuit and as soon as interrupter 361 makes its right contact, establishes a circuit for relay 362. This circuit may be traced from battery through the winding of relay 362, the contact of relay 359, the right contact of interrupter 361 to ground over the upper contacts of cam 309. Relay 362 upon energizing, locks over its 30 inner right contact to ground at the right contact of cam 316. The operation of relay 362 initiates operations which result in the 35 release of relay 330, and the lighting of the signal at the toll operator's position. The release of relay 330 connects the talking conductors to the back contacts of ringing relay 353 and the lighting of the lamp indicates to the toll operator that the talking connection has been cut through and that the automatic ringing of the desired subscriber is proceeding. 40

When the interrupter 361 next makes its left contact, with relay 362 energized, a circuit is established for ringing relay 353 which may be traced from battery, through 45 the winding of relay 353, outer left contact of relay 362, the left contact of interrupter 361, thence to ground through the upper contacts of cam 309. Relay 353 upon energizing, establishes a ringing circuit extending to the incoming selector which may be 50 traced in part from the source of ringing current 363 through lamp 371, contacts of cam 364, lower front contact of relay 353, brush 346, and thence through the ringing relay at the incoming selector, not 55 shown, back to brush 345 and to ground at the upper front contact of relay 353. Relay 353 also opens the talking circuit extending back to the toll line and closes the 60 circuit for relay 302 which may be traced from battery, through the winding of re-

lay 302, the inner upper front contact of relay 353, the right contacts of cam 301, to ground at the left back contact of relay 318. Relay 302 operates in this circuit and locks over its left front contact through 70 cam 301 to ground at the left back contact of relay 318. When the interrupter 361 next opens its left contact, the circuit for ringing relay 353 is opened, but relay 302 remains locked. Reference is made to the 75 above identified application of W. C. Jordan for the operation of the ringing relay at the incoming selector and for other operations incompletely described at this time. 80

Immediately following the initiation of the ringing operation and the deenergization of relay 353, a battery feed coil, not shown, is connected at the incoming selector, across the tip and ring conductors with 85 which brushes 345 and 346 are connected. Relay 359 is again energized closing a circuit for relay 323 which may be traced from battery, through the winding of relay 323, the upper contacts of cam 321, right contact of relay 302, the innermost lower back contact of relay 353, the contact of relay 359, the inner right contact of relay 362 to ground at the right contact of cam 316. Relay 323 energizes in this circuit and closes 90 a circuit for advancing sequence switch 310 into the talking position 15. This circuit extends from battery, through the winding of sequence switch magnet 310, the upper left contact of cam 324, the inner left contact of relay 323, to ground at the right contact of cam 357. As soon as the sequence switch leaves position 14, relay 323 deenergizes, and the circuit of sequence 95 switch magnet 310 is opened. In position 100 15, relay 362 is maintained energized in a circuit extending from battery, through its winding, the contact of relay 359 to ground at the upper right contact of cam 339. Relay 302, however, releases as soon as the 105 sequence switch leaves position 14, since its holding circuit is opened at the lower right contact of cam 301. 110

In response to the answer of the called subscriber, the feed coil above mentioned 115 is disconnected from the tip and ring conductors and relay 359 is again deenergized, opening the circuit of relay 362 which causes the extinguishing of the signal at the toll operator's position to indicate that the called subscriber has answered. The release of relay 362 also closes a circuit for again energizing relay 323, this circuit extending from battery, through the winding of relay 323, the upper contacts of cam 321, inner 120 left back contact of relay 362, the upper contacts of cam 301 and thence to ground at the left back contact of relay 318. Relay 323 now locks over its inner right contact to ground at the lower left contact of cam 339. 125 130

Release of the connection.

Upon the termination of the conversation, the battery feed coil above mentioned, is again connected across the tip and ring conductors. Relay 359 operates, in turn operating relay 362, causing the illumination of the lamp at the toll operator's position. The toll operator then removes her plug from the jack releasing the line switch which removes ground from terminal 275 releasing relay 303. The release of relay 303 closes a circuit from ground at its inner right back contact over the right contacts of cam 320, to battery through the winding of sequence switch magnet 310 for advancing the sequence switch into position 18. As the sequence switch leaves position 15, the locking circuit of relay 323 is opened and this relay releases. With sequence switch 310 in position 18, a circuit is closed for down-drive magnet 365 extending from battery, through the winding of magnet 365, the lower left and upper right contacts of cam 320 to ground at the inner right contact of relay 303. Through the operation of magnet 365, the switch shaft is driven downwardly into normal position where brush 341 engages normal segment 366 closing a circuit for advancing sequence switch 310 into normal position. This circuit may be traced from battery, through the magnet winding of sequence switch 310, the lower right contact of relay 324, segment 366, brush 341 to ground at the upper left contact of cam 339. When the sequence switch 310 leaves position 17, ground is removed from brush 342 at the left contacts of cam 309, initiating the release of the incoming and final selectors for which operations reference is made to the above identified application of W. C. Jordan.

Special calls to outward delay operator.

If for any reason the toll operator should desire to connect with the outward delay operator at the office at which district selector 350 is located, she would, after connecting with that office and receiving the dial signal, dial a code 13. In response to the dialing of the first digit 1, the "A" register is advanced to its first position as previously described, following which the register steering switch 425 advances to position 1. A circuit is now established for relay 423 extending from battery, through the winding of this relay, contact 446 and brush 445 of the "A" register, to ground at the contact of relay 415. Relay 423 energizes, locking over its inner left contact to ground at the inner left contact of relay 414. The second series of impulses which would normally operate the stepping magnet 422 of the "B" register, now operates magnet 417 of the "A" register. The stepping circuit of mag-

net 417 extends from battery, through the left winding of relay 418, winding of magnet 417, outer left front contact of relay 423, brush 416, winding of relay 415, left front contact of relay 413 to ground at the back contact of relay 410. Relay 423 also transfers the circuit of relay 420 for controlling complete stepping of the register magnet from the circuit of magnet 422 to the circuit of magnet 417. Thus the "A" register receives both series of impulses, and since the digits dialed are 1 and 3 respectively, takes a setting corresponding to the sum of the two digits or to position 4. In position 4, a circuit is established for relay 442 extending over contact 447 and brush 448, outer right contact of relay 423 to ground at the inner left contact of relay 414. Relay 442 upon energizing establishes a circuit from ground at its contact over brush 326, the next to the outer contact of relay 318, the lower contacts of relay 355, (the sequence switch of district selector 350 standing in position 3 at this time), terminal 296, and thence to battery through the winding of a relay, at the outward delay operator's position lighting a lamp thereat, to signal that operator as fully set forth in the application of W. C. Jordan. The operation of this relay also causes the removal of ground from terminal 275 releasing relay 303. The release of relay 303 closes a circuit extending from ground over its inner right back contact, the right contacts of cam 320 to battery through the winding of sequence switch magnet 310 for advancing the sequence switch into position 7. In position 7, sequence switch 310 is advanced to position 8 over a circuit extending from battery, through the magnet winding of sequence switch 310, the lower right contact of cam 324, normal segment 366, brush 341, to ground at the upper left contact of cam 339. As soon as the sequence switch reaches position 8, since the relay 307 is not operated, a circuit is immediately established from battery, through the winding of sequence switch magnet 310, lower left contact of cam 324, the outer left back contact of relay 307 to ground at the right contact of cam 308 for advancing the sequence switch into position 9. In position 9, the circuit previously traced through the lower right contact of cam 324 is again established for advancing the sequence switch into normal position. As the sequence switch leaves position 11, the circuits through relays 410 and 402 of the sender are opened and the sender releases as previously described. The outward operator noting the lighting of the lamp may communicate with the distant toll operator by means of the multiple of the trunk line to which the signal operated is individual.

Connections to other operators, such as the repair clerk, information operator, etc.,

are also represented by codes beginning with the digit 1; however, any code other than the code 13 above described brings the translator into operation in the well known manner and the connections are completed to the desired operator under the control thereof.

Signaling the operator upon the permanent signal condition at the sender.

10 It will be recalled that at the time the sender was seized, the monitor switch 450 advanced out of normal position into position 1. At any time thereafter, if the toll operator takes down the connection before 15 the sequence switch of district selector 350 advances out of position 10 releasing relays 410, 413 and 414, a circuit is established for wipe-out relay 439 extending from battery through the winding of this relay, over brush 20 440, the right front contact of relay 404, the left normal contact of relay 413 to ground at the back contact of relay 410. Relay 439 upon operating, causes the release of the sender in the well known manner.

25 If the operator does not wipe out the connection, the monitor switch 450 advances out of position 1 under the control of the slow interrupter 436 provided the operator does not immediately dial the first digit of 30 the wanted line designation. The circuit for advancing switch 450 may be traced from battery, through the winding of magnet 408, interrupter 436, No. 1 contact and brush 438 of switch 450 to ground at the right contact 35 of relay 406. When switch 450 reaches position 3, if relay 406 is still deenergized, the switch is immediately advanced into position 5 over a circuit extending through the winding and contact of magnet 408, the No. 3 40 and No. 4 contacts and brush 438 of switch 450 to ground at the right contact of relay 406. In position 5, a circuit is established from battery through the winding of relay 442, the No. 5 contact and brush 441 of 45 switch 450 to ground at the outer left contact of relay 406. Relay 442 upon energizing, closes a circuit as previously described to bring about the lighting of the lamp corresponding to the trunk used in the connection at the outward delay operator's position 50 and initiates the release of the district selector and the sender.

If the sender fails to release, and therefore the monitor switch is not restored to 55 normal, it will continue to count off time, advancing from position 5 into position 6 under the control of magnet 408 and interrupter 436 over the circuit previously traced. In position 6, a circuit is then established 60 from ground at the outer left back contact to relay 406, brush 441, to battery through lamp 451, signaling the monitoring operator that a permanent signal condition exists and that the sender has not released. If the toll 65 operator starts dialing before switch 450

reaches position 5, the register steering switch 425 will be advanced out of its normal position and a circuit will be established for relay 406, extending from battery through the winding of this relay, brush 443, to ground through brush 444, and switch 450 will, therefore, be immediately advanced into position 7 over a circuit extending from ground at brush 444 thence over brush 443, 70 inner left contact of relay 406, to battery through the contact and winding of stepping magnet 408, and no signal will be given the outward operator, nor will the sender be released.

75 When sequence switch 450 advances from positions 6 to position 7, the circuit for relay 406 is opened and that relay releases. If the operator completes dialing, register switch 425 again closes the circuit of relay 406 operating that relay. If, however, the operator fails to complete dialing and relay 406 remains deenergized due to that fact, switch 450 is advanced from position 7 to position 9 under the control of interrupter 436. Upon reaching position 9, switch 450 80 advances at once into position 10 by reason of the self-interrupting circuit through magnet 408 and its back contact, brush 438, and the right contact of relay 406. In position 10, a short circuit is closed around the left winding of relay 402, over brush 441, and the outer left back contact of relay 406, increasing the current flowing through relay 402 and relay 323 to such an extent as to cause the energization of marginal relay 323. The 85 energization of relay 323 results in advancing the district selector to tell-tale position 95 in which position the toll operator is given a signal to indicate that a stuck sender condition exists, whereupon the toll operator restores the connection releasing the district selector. Reference is made to the above identified application of W. C. Jordan for a more complete description of this operation.

100 Had dialing been completed or the sender functioned correctly, then when the monitor switch 450 reached position 7, relay 406 would have been operated over brushes 443 and 444 and the switch 450 would have advanced at once into position 12. If the sender fails to release under the stuck sender condition, when switch 450 reaches position 11, the circuit of lamp 451 is again established indicating to the monitoring operator 105 that the sender has failed to release. Since the remaining functions of the monitor switch do not directly concern the present invention, they will not be further described herein.

110 What is claimed is:

1. In a registering system, a pair of registering devices, a control circuit, means for normally extending said control circuit to said registering devices in succession, means 115 operated over said control circuit for posi- 120

tioning said registering devices, and means operated in response to the positioning of said first registering device in a particular position to transfer the extension of said control circuit from the second registering device back to the first registering device whereby said first registering device may be further positioned.

2. In a registering system, a pair of registering devices, a control circuit, means for normally extending said control circuit to said registering devices in succession, means operated over said control circuit for positioning said registering devices, and a relay operated in response to the positioning of said first registering device in a particular position to transfer the extension of said control circuit from the second registering device back to the first registering device whereby said first registering device may be further positioned.

3. In a registering system, a pair of registering devices, a control circuit, a steering switch for normally extending said control circuit to said registering devices in succession, means operated over said control circuit for positioning said registering devices, and means operated in response to the positioning of said first registering device in a particular position to transfer the extension of said control circuit from the second registering device back to the first registering device whereby said first registering device may be further positioned.

4. In a registering system, a pair of registering devices, an impulse relay, a control circuit controlled thereby, means for normally extending said control circuit to said registers in succession, means operated over said control circuit for positioning said registering devices, and means operated in response to the positioning of said first registering device in a particular position in response to the first series of impulses received by said relay to transfer the extension of said control circuit from said second registering device back to the first registering device whereby said first registering device is also further positioned in response to the second series of impulses received by said relay.

5. In a registering system, a pair of registering devices, a control circuit, a steering switch for normally extending said control circuit to said registering devices in succession, means operated over said control circuit for positioning said registering devices, a circuit closed in successive positions of said switch for insuring complete positioning of said registering devices, and means operated in response to the positioning of said first registering device in a particular position to transfer the extension of said control circuit from the second registering device back to the first registering device and to transfer

said second circuit from the second registering device back to the first registering device.

6. In a registering system, a pair of registering devices, operating magnets therefor, an impulse receiving relay, a quick acting relay, a control circuit controlled by said impulse relay, a steering switch adapted in successive positions to extend said control circuit in parallel through said quick acting relay and said operating magnets, a circuit for said magnets controlled at contacts of said quick acting relay, means controlled by said magnets when completely energized to open the circuit of said quick acting relay, and means operated in response to the positioning of said first registering device in a particular position to transfer the extension of said control circuits from the magnet of the second registering device back to the magnet of the first registering device whereby said first registering device may be further positioned and to transfer the branch of said control circuit extending through said quick acting relay from connection with the magnet of said second registering device back to connection with the magnet of said first registering device.

7. In a registering system, a pair of registering devices, a control circuit, means for normally extending said control circuit to said registering devices in succession, means operated over said control circuit for positioning said registering devices, means operated in response to the positioning of said first registering device in a particular position to transfer the extension of said control circuit from the second registering device back to the first registering device whereby said first registering device may be further positioned, and means operated in response to the combination of the first positioning and a particular second positioning of said first registering device for establishing a special signaling circuit.

8. In a telephone exchange system, an incoming line, a register sender, means for associating said sender with said incoming line, a relay in said sender, means for establishing a pulsing circuit over said incoming line and including said relay, and means for establishing a second circuit for said relay to render said relay unresponsive to disturbances on said incoming line.

9. In a telephone exchange system, an incoming line, a register sender, means for associating said sender with said incoming line, a relay in said sender, means for establishing a pulsing circuit over said incoming line and including said relay, and means for establishing a second circuit for said relay during a predetermined interval to render said relay unresponsive to disturbances on said incoming line.

10. In a telephone exchange system, an

- incoming line, a register sender, means for associating said sender with said incoming line, a relay in said sender for establishing a pulsing circuit over said incoming line and including said relay, a slow releasing relay, means for closing and opening a circuit for said slow releasing relay to establish a holding circuit for said relay for a predetermined interval to render said first relay unresponsive to disturbances on said incoming line.
11. In a telephone exchange system, an incoming line, a register sender, means for associating said sender with said incoming line, a relay in said sender, means for establishing a pulsing circuit over said incoming line and including said relay, a slow releasing relay, a timing device, means under the control of said timing device for closing and opening a circuit for said slow releasing re-

lay to establish a holding circuit for said first relay for a predetermined interval to render said first relay unresponsive to disturbances on said incoming line.

12. In a telephone system, an incoming line, a register sender, means for associating said sender with said incoming line, a relay in said sender, means for establishing a pulsing circuit over said incoming line and including said relay, and means operative upon the association of said sender with said line for establishing a temporary holding circuit for said relay to render said relay unresponsive to disturbances on said incoming line.

In witness whereof, I hereunto subscribe my name this 25th day of February A. D., 1924.

RUSSELL O. COVELL.
